UNITED STATES PATENT OFFICE.

JAMES C. KEER, OF COLUMBUS, OHIO.

PATTERN-CLAMP.

1,193,699.

Specification of Letters Patent. Patented Aug. 8, 1916.

Application filed December 30, 1914. Serial No. 879,786.

To all whom it may concern:

Be it known that I, JAMES C. KEER, a citizen of the United States, residing at Columbus, in the county of Franklin and State of Ohio, have invented certain new and useful Improvements in Pattern-Clamps, of which the following is a specification.

My invention relates to the improvement of pattern clamps or devices for uniting the wooden pattern sections during the course of the construction of a pattern.

The objects of my invention are to provide simple and effective clamping or connecting devices adapted to unite or firmly bind together previously glued pattern sections; to so construct my improved clamping devices as to admit of previously glued sections of wood patterns being firmly drawn into connection with each other and retained in such connection until the glue has sufficiently dried; to so construct said clamping devices as to permit of the quick withdrawal of the same by the aid of an ordinary claw hammer and to produce other improvements, the details of which will be more fully pointed out hereinafter.

The preferred embodiment of my invention is shown in the accompanying sheet of drawings, in which similar characters of reference designate corresponding parts, and in which:

Figure 1 is a plan view of three pattern segments united by my improved clamps, Fig. 2 is a side elevation of the same, Fig. 3 is a sectional view on line 3-3 of Fig. 2, Fig. 4 is a side elevation of a modified form of clamping plate, and Fig. 5 is a plan view of the same.

Each of my improved clamping devices comprises a clamping plate 1, which may be of the disk form shown in Figs. 1 and 2 or may be of other desirable outline, such for instance as that shown in Figs. 4 and 5. The upper or outer face of the plate is preferably beveled as shown, imparting thereto a substantially frustum cone shaped form. From the center of the upper flattened portion of the plate extends upwardly a short stem 2 which in turn has its upper end formed with an annular flange 3, resulting in the production of an annular stem recess 4. The underside of the plate 1 is preferably slightly concaved as indicated at 5 and a nail opening 6 is formed centrally through the body of the plate and its stem. In order to illustrate the opera-

tion of my device, I have shown three sections of a partially completed circular wood pattern, the curved segment or section 7 being in the usual manner affixed to the upper sides of the segments 8 by gluing. The glue having been applied to the contacting surfaces of the segments and it being desired to bind or clamp the upper segment 7 in connection with the segments 8 during the drying of the glue, the clamping plates 1 are successively placed with their concaved under sides upon the upper face of the outer pattern segment and a nail of suitable length driven downward through the opening 6 of the stem and plate body 1, the nail piercing the upper segment and entering the lower segment in the manner indicated in the drawing. By driving the head of the nail tightly against the upper end of the plate stem, it is obvious that the binding plate 1 may have the marginal portion of its underside due to its concave form, clamped or pressed so closely into engagement with the upper surface of the upper segment, as to not only draw said segment into extremely close relation with each other, but to squeeze from between said segments the surplus glue.

As will be apparent, the under surface of the plate 1 is concaved to present a marginal portion which may readily adapt itself to the surface of the work by embedding itself in the wood, thus assuring an even pressure.

It has generally been a common practice among pattern makers to draw or clamp the segments of the pattern together, by the aid of what is well known as a screw clamp, but such a clamp in addition to requiring considerable manipulation, does not always provide a perfect vertical pressure of its jaws on the united segments, with the result that the contact or pressure of the segments against each other is not uniform.

When the various segments of the pattern to be produced have been thus united and the glue between the segments has dried sufficiently, each of the clamps may be quickly and effectively disconnected from the pattern segments and the nail withdrawn therefrom by engaging the annular stem recess 4 by the claws or fingers of an ordinary claw hammer or other similar or convenient tool and pressing downward on the handle of the tool to attain the desired nail pulling leverage. This being accomplished, the upper side of the partially completed pattern may be dressed to the desired

extent and the operation repeated with reference to the next succeeding segments.

By the use of my improved clamping devices, it will be understood that the proper 5 uniting of the pattern segments or sections and the withdrawal of the nails may be accomplished so quickly and effectively as to make the substitution of my improved "nail clamps" for the ordinary pattern clamps, 10 extremely desirable.

What I claim, is:

A pattern clamp comprising a plate, and an integral central upwardly extending

stem, the latter having a peripheral recess formed between the body of the plate and 15 the upper end of the stem, said plate and stem having a nail receiving opening there-through, said plate being further provided with a concaved under surface.

In testimony whereof I affix my signature 20 in presence of two witnesses.

JAMES C. KEER.
